CLAIM

I claim the ornamental design for a keyboard, as shown and described.

DESCRIPTION

FIG. 1 is an exploded, perspective view of a first embodiment of a keyboard, showing my new design, with the detachable wrist rest separated from the keyboard;

FIG. 2 is an exploded, top plan view thereof;

FIG. 3 is an exploded, bottom plan view thereof;

FIG. 4 is an exploded, rear elevational view thereof;

FIG. 5 is an exploded, front elevational view thereof;

FIG. 6 is an exploded, right side elevational view thereof; and

FIG. 7 is an exploded, left side elevational view thereof.

FIG. 8 is an assembled, perspective view of the keyboard of FIGS. 1-7, showing my new design, with the detachable wrist rest attached to the keyboard;

FIG. 9 is an assembled, top plan view thereof;

FIG. 10 is an assembled, bottom plan view thereof;

FIG. 11 is an assembled, rear elevational view thereof;

FIG. 12 is an assembled, front elevational view thereof;

FIG. 13 is an assembled, right side elevational view thereof;

FIG. 14 is an assembled, left side elevational view thereof;

FIG. 15 is an exploded, perspective view of a second embodiment of a keyboard, showing my new design, with the detachable wrist rest separated from the keyboard;

FIG. 16 is an exploded top plan view thereof;

FIG. 17 is an exploded, bottom plan view thereof;

FIG. 18 is an exploded, rear elevational view thereof;

FIG. 19 is an exploded, front elevational view thereof;

FIG. 20 is an exploded, right side elevational view thereof; and

FIG. 21 is an exploded, left side elevational view thereof.

FIG. 22 is an assembled, perspective view of the keyboard of FIGS. 15-21, showing my new design, with the detachable wrist rest attached to the keyboard;

FIG. 23 is an assembled, top plan view thereof;
